UNITED STATES PATENT OFFICE.

CHARLES N. SOWDEN, OF GUANTÁNAMO, CUBA.

SWIVEL LAMP-HOLDER.

1,075,951.

Specification of Letters Patent. Patented Oct. 14, 1913.

Application filed November 1, 1912. Serial No. 728,976.

To all whom it may concern:

Be it known that I, CHARLES N. SOWDEN, a citizen of Canada, at present residing at Guantánamo, Santiago de Cuba Province, Cuba, have invented a new and Improved Swivel Lamp-Holder, of which the following is a full, clear, and exact description.

My invention relates to means for causing a lamp to be automatically turned in the direction in which the vehicle is turned, so that if the vehicle is turned to the right or left, a lamp will be turned accordingly.

It is a design of my invention to provide an improved means for effecting the automatic turning of the lamp; to improve the means for swiveling the lamp; to provide an improved spring-actuated means tending normally to return the lamp to the neutral position; to provide for changing the location 20 of the neutral position relatively to the direction of travel; and to provide actuating means for a pair of lamps, so arranged that one lamp will turn automatically in the direction in which the vehicle turns, while the 25 opposite lamp will be under the control of the operator and subject to manually-controlled means whereby said opposite lamp may be turned in the opposite direction to the turning of the vehicle.

It is also a design of my invention to improve in various particulars, devices of the indicated character, to the end that efficiency in operation may be promoted, as well as economy in manufacturing and simplicity 35 of adjustment and control.

The distinguishing features of my invention, and the important structural elements characterizing the preferred embodiment which is illustrated as an example, will be 40 more particularly explained in the specific description hereinafter to be given.

Reference is to be had to the accompanying drawings forming a part of this specification, in which similar characters of reference indicate corresponding parts in all the 45 views.

Figure 1 is a side elevation of a portion of an automobile showing a practical embodiment of my invention applied thereto; 50 Fig. 2 is a plan view of the elements shown in Fig. 1; Fig. 3 is a transverse vertical section on a larger scale, approximately on a line corresponding with the line 3—3 of Fig. 5; Fig. 4 is a side elevation of the parts

shown in Fig. 3; and Fig. 5 is a sectional 55 plan view on a still larger scale, approximately on a line corresponding with line 5—5 of Fig. 3.

In constructing the particular form of my invention illustrated as an example, a vertical fork or yoke 10 is adapted to receive a lamp A, of any approved form, and at the base of the yoke a peripheral groove 11 is formed, in which a rope, cord or other flexible element 12 is given a partial turn, 60 it being fastened as at 12^a on one side of the yoke, and extending at the front to the opposite side, to a vertical sheave 13, around which the rope is given a partial turn and secured at its opposite end as at 12^b. The 65 sheave 13 is suitably journaled as herein-after described at one side of the yoke, and in practice a second sheave 13^a is provided at the opposite side, but only one sheave is used in practice, according to which side of 70 the vehicle the lamp holder is mounted. To the sheave is secured a depending lever 14, to the lower, free end of which a rope or other flexible element 15 is secured, to rock 75 the lever and give a partial turn to the sheave 13, and hence a similar turn to the yoke 10, through the rope 12. The rope 15 passes rearwardly to an idler 16 suitably mounted as on a bracket 16^a on the chassis 17, and extends thence transversely to the 80 opposite side of the vehicle, where it has suitable connection with the arm 18 of the steering knuckle 18^a, in the event the invention 85 is applied to an automobile.

It will be seen from the plan view, that 90 the lamp yoke 10 and the described appurtenances and actuating devices are duplicated at each side of the machine, and it will be understood that in practice, the arms 18 are connected in the usual manner for operation in unison. In the present instance I have shown the transverse stretch 15^a of the 95 rope as secured to a post 19 on an arm 18, for the automatic turning of the lamp-holder with the steering devices.

The manually-controlled means illustrated for turning the lamp holders, comprise in the present instance, a rope or its equivalent 100 connected to each transverse stretch 15^a as at 20, in any suitable manner; at the point 105 indicated by the numeral 22, there extends a further stretch of rope 23 to the lower end of a hand-pull or other actuating element 24,

to be actuated by hand for exerting a rearward pull on the stretch 23 and hence on the rope 21, and through the stretch 15^a, on the rope 15, to exert a rearward pull on the latter. From the point 22 also, or from an adjacent point, there extends from each rope 21, a stretch 25 of rope, which is given a bend around an idler 26 suitably supported on the vehicle, and to a connection with the lower 10 end of a lever 27 or its equivalent, to be actuated by the pedal 28, so that the lamp holder may be thus turned either by the foot of the operator, or by hand, as previously described, and as will be hereinafter more 15 fully explained.

The yoke 10 is supported from the chassis bracket 29, being secured to the latter as is usual. On said bracket is a bed plate 30, having depending brackets 31 through 20 which the pulleys 13, 13^a are journaled, as by a pin 32, the threaded end of which may receive a nut 32^a. On the bed 30 a table 33 rests, in which is an annular groove 34 that receives a curved compression spring 35. 25 The ends of the spring 35 terminate adjacent to a stop 36 suitably secured as by a screw 36^a or the like, to the table 33, the ends of the spring abutting against washers 37 (Fig. 5) that bear normally against opposite sides of the stop 36. Between the washers 37, and fitting a curved groove 36^b in the stop 36, is a depending lug 38 in fixed relation to the yoke 10 and depending from the under side thereof, the arrangement being 30 such that as the yoke is turned under a pull of the rope 12, the lug 38 will engage one of the washers 37, according to the direction in which the yoke is turned, and place the spring 35 under compression. Since the 35 groove 36^b extends through each side of the stop 36, the lug 38 is free to move in either direction in response to the turning of the yoke, to contact with either washer 37. The 40 location of the stop 36 determines the neutral position of the spring, and in order that the location of the stop may be changed to dispose the lamp so as to throw its rays in a given direction, the table 33 carrying the said stop may be turned on its axis in a horizontal plane on the bed 30, and locked in the 45 adjusted position. For the described purpose a pin 39 (Fig. 3) rises from the upper end of the bracket 29, extends through the bed 30, and into one of a curved series of 50 recesses 39^a (Fig. 5) on the under side of the table 33, it being understood that to effect the desired adjustment the table 33 and its supported yoke 10, with the appurtenances, are lifted off the bed 30 and replaced in the 55 new position.

Between the table 33 and the yoke 10, ball bearings 40 are arranged and conveniently located between opposing surfaces of said parts. Similarly at the eye 41 of the swivel 60 yoke 10, ball bearings 42 are arranged be-

tween the surface of the said eye and the under side of the cap 43 fitting the spindle 44 on which the yoke is swiveled. The spindle receives at its upper end a nut 45 and jam nut 46.

With the described arrangement it will be seen that the stops can be so set that the light rays will be thrown in the direction of travel of the car, and by reason of the described connections between the lever 16 and the steering knuckle, if the vehicle is turned to the right, that lamp at the right hand side (the upper portion of Fig. 2) will be turned to the right, while the tension on the cords 15, 15^a of the left hand lamp will be relieved, whereby by the manually-controlled means (either the pedal or hand device) the left hand lamp can be turned to the left. Thus one of the lamps will be automatically turned and the other will be subject to manual control. The stops of the lamps can be so set that the lights when automatically turned, will swing to the full extent that the wheels turn, and one of the lamps will, at the same time, be always under the control 90 of the operator, so as to be turned in the opposite direction from that in which the wheels turn.

Having thus described my invention, I claim as new, and desire to secure by Letters Patent:—

1. The combination with a vehicle, of a pair of lamp holders mounted to turn, connections between the respective holders and parts of the vehicle that turn oppositely 100 when the vehicle is turned, the turning of the vehicle in one direction serving to turn one of the lamps in the direction in which the vehicle is turned, and manually controlled means connected with the holders 105 and adapted to turn a holder in the opposite direction from the automatic turning of the other holder.

2. The combination with a vehicle, of lamp holders, means for automatically turning one holder when the vehicle is turned in one direction and for automatically turning the other holder when the vehicle is turned in the opposite direction, the automatic turning of the holders being in the direction 115 in which the vehicle is turned, and manually-controlled means in connection with each lamp for turning the same, the manually-controlled means being operative when the automatic means of a particular lamp is 120 idle.

3. The combination with a vehicle, of a lamp holder mounted to turn at each side of the vehicle, means for automatically turning a lamp at one side in the direction in which 125 the vehicle turns, means for automatically turning the lamp at the other side in the opposite direction with the opposite turning of the vehicle, and manually-controlled means connected with each lamp, and opera- 130

tive to turn the lamp at one side in the opposite direction from the automatic turning of the other lamp.

4. A lamp holder, comprising a swiveled lamp-supporting member, a curved compression spring supported beneath the lamp-supporting member and opposing the turning thereof in either direction, a stop between the ends of the curved compression spring, and an element on the lamp-supporting member movable into engagement with the spring at that side of the stop toward which the lamp supporting member is turned.

5. A lamp-holder, comprising a swiveled lamp-supporting member, a curved compression spring supported beneath the lamp-supporting member and opposing the turning thereof in either direction, a stop between the ends of the curved compression spring, an element on the lamp-supporting member movable into engagement with the spring at that side of the stop toward which the lamp-supporting member is turned, and means for changing the location of the said stop and the corresponding position of the spring.

6. In a lamp holder, the combination of a yoke having a groove at the base thereof, a pulley supported adjacent to the yoke to ro-

tate on an axis at an angle to the axis of rotation of the yoke, a flexible element secured to the base of the yoke and having a partial turn thereon, and secured to the pulley and having a partial turn thereon, a lever secured to said pulley to turn the same, and means for throwing said lever.

7. The combination in a lamp holder, of a supporting bracket, a vertical spindle thereon, a table, means for adjusting the table axially and securing it in different adjusted positions, a stop on said table, a coiled spring in curved form seated on said table, washers at each side of the stop against which the ends of the spring abut, a lamp-holding yoke swiveled on the spindle above the table and spring, a depending member on said yoke projecting into the stop and movable against either washer according to the direction of turning of the yoke, and means for turning said yoke.

In testimony whereof I have signed my name to this specification in the presence of two subscribing witnesses.
